UNITED STATES PATENT OFFICE

161,879

CHRISTMAS STOCKING

Miriam G. Sauer, Dallas, Tex., assignor of fifty per cent to Ruth Z. Apple, Dallas, Tex.

Application January 30, 1950, Serial No. 7,574

Term of patent 3½ years

(Cl. D47—7)

To all whom it may concern:

Be it known that I, Miriam G. Sauer, a citizen of the United States, residing at Dallas, in the county of Dallas and State of Texas, have invented a new, original, and ornamental Design for a Christmas Stocking, of which the following is a specification, reference being had to the accompanying drawing, forming part thereof.

The single figure is a perspective view of a Christmas stocking, showing my new design.

The side of the Christmas stocking opposite the side shown is conventionally plain.

I claim:

The ornamental design for a Christmas stocking, as shown and described.

MIRIAM G. SAUER.
